UNITED STATES PATENT OFFICE.

WILLIAM C. MILES, OF NEW YORK, N. Y., ASSIGNOR TO MAGNUS ELECTRIC COMPANY, INC., A CORPORATION OF NEW YORK.

SNAP SWITCH.

Application filed December 12, 1922. Serial No. 606,359.

To all whom it may concern:

Be it known that I, WILLIAM C. MILES, a citizen of the United States, and a resident of New York city, borough of Manhattan, county and State of New York, have invented a new and useful Improvement in Snap Switches, of which the following is a specification.

This invention relates to electric switches 10 of the snap type.

An important object of the invention is to provide a device of the character mentioned which is simple in construction, inexpensive to manufacture and reliable in operation.

15 A further object of the invention is to so construct the several cooperative elements of the device that they may be easily assembled and effectively retained in their respective cooperative positions to provide a compact and efficient switch unit.

20 Further objects and certain advantages of the invention will become apparent from the following description when taken in connection with the accompanying drawings in 25 which,

Figure 1 is a plan view of a switch plug particularly adapted for the reception of the device embodying my invention.

Figure 2 is a longitudinal sectional view 25 taken on line 2--2 of Figure 1.

Figure 3 is a transverse sectional view taken on line 3--3 of Figure 2.

Figure 4 is a view in elevation of the switch plug with a section of the casing removed in order to illustrate the several switch elements embodying my invention in their respective positions.

Figure 5 is a transverse sectional view taken on line 5--5 of Figure 2.

40 Figure 6 is a perspective view of a switch unit.

With reference to the drawings wherein I have elected to show my invention as embodied in a switch plug, notwithstanding the 45 fact that the same is equally adapted to be used for example in connection with pendant switches, thermally controlled apparatus, and in various other instances where it is desired to employ a circuit closer operating with a snap action to open and close an electric circuit, the numeral 10 indicates a housing comprising complementary sections 50 11, so moulded or constructed as to provide grooves 12, terminating in pockets 13, which

55 form with each other chambers 14, when the

sections are united as by means of bolts 15. In constructing the housing 10 the sections 11 thereof are so formed as to provide intermediate the grooves 12 and pockets 13, divisional walls 16 and 17, respectively, the adjacent ends of which function as abutments adapted to receive therebetween a switch block indicated as a whole by the numeral 18 and hereinafter more particularly described. The grooves 12 are adapted for the reception of conductor strips 19 and 20 connected respectively to conductors 21 and 22 by means of screws 23, whereas the pockets 13 are adapted for the reception of contact jaws 24 and 25 into which the conventional form of terminals such as are employed in connection with electric irons, toasters and the like, not shown, are adapted to be inserted. In the embodiment of my invention the conductor strip 20 is connected directly to the contact jaw 25 and is held in engagement therewith by means of a screw 26 whereas the contact jaw 24 is adapted to be electrically connected with the conductor strip 19 by means of an oscillating circuit 70 closer indicated as a whole by the numeral 27.

The switch unit 28 shown most clearly in Figure 6 is adapted to be positioned within the housing 10 in such a manner that when the sections 11 are connected together the divisional walls 16 and 17 function cooperatively to retain the switch block 18 together with the several associated elements against lateral movement thus insuring a proper position of the same within the housing under all conditions. The switch block 18 may be constructed from fibre, porcelain, or other suitable insulating material and is provided with a longitudinal groove 29 95 adapted for the reception of a reciprocating operating member 30, the opposite ends of which project through openings 31 formed in the housing 10, the ends of the operating member being provided with push buttons 32 which function not only to facilitate the operation of the circuit closer 27 but as a means for limiting the movement of the operating member 30 by reason of the fact that they are adapted to alternately abut opposite ends of the switch block 18 as the operating member is reciprocated. This operating member is provided with an opening 33 to receive one end of a tension spring 34 adapted to operate within an elongated 105 110

opening 35 formed in the switch block 18. The opposite end of the tension spring 34 extends through the elongated opening 35 and is looped through the opening 27' 5 formed in the circuit closer 27 thus providing such a connection that when the operating member 30 is reciprocated the circuit closer 27 is oscillated with an intermittent snap action to either open or close the circuit as the case may be. This circuit closer is of such a nature that it may be readily stamped and thereafter shaped to provide a pair of more or less resilient arms 36 carrying contacts 37, the arms being formed integrally with a yoke element 38, to the bridge portion 39 of which the tension spring 34 hereinbefore mentioned is suitably connected. The yoke 38 is so shaped as to provide wings 40 adapted to engage the switch block 18 to limit the movement of the circuit closer 27 when the reciprocating member 30 is so operated as to open the circuit.

In order that the circuit closer 27 may oscillate freely and in order that complicated pivotal connection between this member and the switch block 18 may be avoided, I have provided the yoke 38 with a pair of depending spurs 41 which function as pivotal elements supported by the switch block 18 and upon which the circuit closer 27 is adapted to oscillate. As a means for preventing excessive wear upon the switch block 18 in the event the same is constructed from such material as fibre, and in order to overcome excessive wear upon the spurs 41 in the event the switch block is constructed from such material as porcelain, which is more or less abrasive in its nature, I have provided a pair of bearings 42 which are depressed or countersunk thus forming seats or pockets into which the pointed ends of the spurs 41 are adapted to operate. These pockets 42 may be easily moulded or otherwise anchored within the switch block 18 and function not only as a means for eliminating excessive friction between the circuit closer 27 and switch block 18 as well as a means for eliminating excessive wear upon either or both of these elements but also function cooperatively with the spring 34 as a means for retaining the circuit closer 27 properly positioned upon the switch block 18 under all conditions and regardless of the number of oscillations imparted to the circuit closer per unit of time.

The switch block 18 is provided at one end thereof with a groove 43 which is adapted for the reception of a contact strip 44 having a contact area 44' and suitably connected to the contact jaw 24 by means of a screw 45. In order to prevent displacement of the contact strip 44 with respect to the switch block 18 particularly during assembly of the switch unit 28, I have provided the same with shoulders 46 and 47

adapted to engage opposite faces of the switch block when the unit is assembled. Adjacent the groove 43 there is provided an angular slot 48 adapted for the reception of the angularly bent portion 49 of the contact strip 19, the extreme end 50 of which functions as a contact adapted to cooperate with the circuit closer 27 when the reciprocating member 30 is so operated as to close the circuit. By reason of the angular disposition of the slot 48 and the peculiar manner in which the end of the contact strip 19 is bent, it is obvious that the same may be effectively retained in position within the slot 48 in the absence of shoulders corresponding to those of the contact strip 44 and indicated by the numerals 46 and 47. Since the contact strip 44 and the angularly bent portion 49 are singly fitted into their respective grooves and since their outer edges are maintained flush with the end of the switch block 18, it is obvious that when the switch block 18 is positioned within the housing 10 both the gripping contact 24 and the contact strip 19 are prevented from moving either longitudinally or transversely and it therefore becomes unnecessary to employ screws or other fastening means for retaining these elements properly positioned within the casting 10.

Assuming that the device is attached to an electric iron or other electrical apparatus and it is desired to close the circuit therethrough, the reciprocating member 30 is moved from its full line position shown in Figure 4 to its dotted line position whereupon the tension exerted by the spring 34 upon the circuit closer 27 is transferred to a point beyond the oscillating center of the circuit closer 27 with the result that as soon as this condition is reached the circuit closer 27 is so thrown with a quick snap action as to bring the contact area 37 of the arms 36 into engagement with the contact areas 50 and 44' of the conductors 19 and 44, respectively. To open the circuit with a quick snap action it becomes necessary only to move the reciprocating member 30 from its dotted line position to the full line position shown in Figure 4 whereupon the operation of the circuit closer 27 is the reverse of that above described.

In assembling the switch unit 28, the contact strips 19 and 44 are fitted into the slots or grooves formed in one end of the switch block 18, then the reciprocating member 30, with the spring 34 attached thereto, is introduced into the groove 29, the free end of the spring 34 being thereby projected an appreciable distance through the elongated opening 35. The next step in assembling the unit resides in attaching the circuit closer 27. This is done most expeditiously by passing the hook at the free end of the spring 34 through the opening 27' formed

in the bridge portion 39 of the yoke element 38, while holding the circuit closer 27 in an inverted position with the arms 36 extending rearwardly of the switch block 18, or 5 away from the contact strips 19 and 44. After the spring has been thus attached to the bridge portion 39, the circuit closer is rotated or turned about its point of connection with the spring 34, for example, in a 10 clockwise direction with reference to Figure 4, thereby bringing the closer into its proper position upon the switch block with the spurs 41 seated within the bearings 42. During this inverting movement of the circuit closer, the spring 34 will yield a sufficient distance without straining it beyond its elastic limit to permit the ends of the arms 36 to pass over the upper face of the switch block 18.

20 Having thus described my invention, I claim:

1. In an electric switch mechanism, a casing, a switch unit adapted to be assembled exteriorly of and thereafter introduced as 25 a unit into said casing, said unit comprising a switch block having contact receiving openings formed therein, contacts arranged within said openings and adapted to assume such a position with respect to said casing when 30 said unit is introduced therein that the casing functions as a means for maintaining said contacts within their respective openings and a circuit closer adapted to be moved into and out of engagement with said contacts.

2. In an electric switch mechanism, a casing, a switch unit adapted to be assembled exteriorly of and thereafter introduced as a unit into said casing, said unit comprising 40 a switch block having contact receiving openings formed therein, contacts arranged within said openings and having interlocking engagement with said switch block, said contacts each being adapted to assume such a 45 position with respect to said casing when said unit is introduced therein that the casing functions as a means for maintaining said contacts within their respective openings and a circuit closer adapted to be moved into and out of engagement with said contacts.

3. In an electric switch mechanism, a casing, a switch unit adapted to be assembled exteriorly of and thereafter introduced as 55 a unit into said casing, said unit comprising a switch block having a slot formed therein and provided with an opening, an operating member having a spring attached thereto, said operating member being adapted to be so introduced into said slot that said 60 spring projects through said opening, a circuit closer adapted, while in an inverted position, to be attached to the projecting end of said spring upon that side of said switch block opposite said groove and to be there-

after swung around its point of connection with said spring to operating position upon said switch block, said spring being utilized to retain said operating member within said groove and to maintain said circuit closer 70 properly positioned upon said switch block, and contacts into and out of engagement with which said circuit closer is adapted to be moved.

4. In an electric switch mechanism, a casing adapted for the reception of a pair of contacts, a switch unit adapted to be assembled exteriorly of and thereafter introduced into said casing, said unit comprising a switch block having a groove formed in one 80 side thereof and an opening extending therethrough, an operating member having a spring attached thereto and adapted to be so introduced into said groove from one side of said block that said spring extends 85 through said opening to the opposite side of said block, a circuit closer adapted, while in an inverted position, to be attached to the projecting end of said spring and to thereafter be moved about its point of connection with said spring to operating position upon said switch block, said spring being utilized to retain said operating member 90 within its groove and to maintain said circuit closer properly positioned upon said switch block and to effect movement, when co-operating with said operating member, of said circuit closer into and out of engagement with said contacts.

5. In an electric switch mechanism, a casing adapted for the reception of a pair of contacts, a switch unit adapted to be assembled exteriorly of and thereafter introduced into said casing, said unit comprising a switch block having a groove formed in one side thereof and an opening extending therethrough, an operating member having a spring attached thereto and adapted to be so introduced into said groove from one side of said block that said spring extends 105 through said opening to the opposite side of said block, a circuit closer adapted, while in an inverted position, to be attached to the projecting end of said spring and to thereafter be moved about its point of connection 110 with said spring to operating position upon said switch block, said spring being utilized to retain said operating member within its groove and to maintain said circuit closer properly positioned upon said switch block 115 and to effect movement, when co-operating with said operating member, of said circuit closer into and out of engagement with said contacts, and seats carried by said switch block and formed from a material unlike 120 that of said switch block, said seats being adapted to receive said circuit closer and function as bearings therefor.

6. In an electric switch mechanism, a casing adapted for the reception of a pair of 125

contacts, a switch unit adapted to be assembled exteriorly of and thereafter introduced into said casing, said unit comprising a switch block having a groove formed in one side thereof and an opening extending therethrough, an operating member having a spring attached thereto and adapted to be so introduced into said groove from one side of said block that said spring extends through said opening to the opposite side of said block, a circuit closer adapted while in an inverted position to be attached to the projecting end of said spring and to thereafter be moved about its point of connection with said spring to operating position upon said switch block, said spring being utilized to retain said operating member within its groove and to maintain said circuit closer properly positioned upon said switch block and to effect movement, when co-operating with said operating member, of said circuit closer into and out of engagement with said contacts and extensions carried by said circuit closer to limit the movement of the same upon disengagement of said circuit closer with said contacts.

7. In an electric switch mechanism, a casing, a switch unit adapted to be assembled exteriorly of and thereafter introduced into said casing, said unit comprising a switch block having a pair of openings formed therein at an angle with respect to each other, a pair of contacts adapted to be introduced into said openings from the end of said block, one of said contacts being cut away to provide shoulders adapted to engage opposite faces of said block, whereas the other of said contacts is bent upon itself to provide an interlocking engagement with said block, a circuit closer carried by said switch block and means associated with said switch block for moving said closer into and out of engagement with said contacts.

8. In an electric switch mechanism, a casing, a switch unit adapted to be assembled exteriorly of and thereafter introduced into said casing, said unit comprising a switch block having a pair of openings formed therein at an angle with respect to each other, a pair of contacts adapted to be introduced into said openings from the end of said block, one of said contacts being cut away to provide shoulders adapted to engage opposite faces of said block whereby the contact provided with said shoulders is retained against longitudinal displacement whereas the other of said contacts is bent upon itself to provide interlocking engagement with said switch block to retain said other contact against longitudinal displacement, both of said contacts being so positioned when said unit is introduced into said casing that the casing functions as a means for maintaining said contacts against transverse displacement with respect to each

other, and a circuit closer adapted to be moved into and out of engagement with said contacts.

9. In an electric switch mechanism, a casing, a switch unit adapted to be assembled exteriorly of and thereafter introduced into said casing, said unit comprising a switch block having a groove formed therein and provided with an opening, an operating member having a spring connected thereto, said operating member being adapted to be so introduced into said groove from one side of said switch block that said spring projects through said opening to the other side of said block, a circuit closer in the form of a yoke having a pair of arms extending therefrom at right angles thereto, said yoke being adapted while in an inverted position to be connected to the projecting end of said spring and to thereafter be moved about its connection with said spring from its inverted position to operating position upon said switch block, and a pair of contacts adapted to cooperate with said arms to close the current through said circuit closer when said circuit closer is moved from one position to the other.

10. In an electric switch mechanism, a casing, a switch unit adapted to be assembled exteriorly of and thereafter introduced into said casing, said unit comprising a switch block having formed therein contact receiving openings, a groove and a spring receiving opening, an operating member having a spring connected thereto and adapted to be so introduced into said groove from one side of said block that said spring extends through said spring receiving opening, a circuit closer in the form of a yoke having a pair of arms extending therefrom at right angles thereto, said yokes being adapted while in an inverted position to be connected to the projecting end of said spring and to thereafter be moved about its connection with said spring from its inverted position to operating position upon said switch block, a pair of contacts adapted to be introduced into said contact receiving openings, and having interlocking engagement with said switch block, said contacts being each adapted to assume such a position with respect to said casing when said unit is introduced therein that the casing functions as a means for maintaining said contacts within their respective openings.

11. In an electric switch mechanism, a casing adapted for the reception of a pair of contacts, a switch unit adapted to be assembled exteriorly of and thereafter introduced as a unit into said casing, said unit comprising a switch block having an open groove formed in one side thereof and provided with a spring receiving opening, an operating member having a spring attached thereto, said operating member being adapt-

- ed with said spring attached thereto to be so introduced into said slot that said spring is thereby projected through said opening and a circuit closer adapted to be connected to the projecting end of the spring and positioned upon said switch block.
12. In an electric switch mechanism, a casing, a switch unit adapted to be assembled exteriorly of and thereafter introduced as a unit into said casing, said unit comprising a switch block having a groove formed therein and a spring receiving opening communicating with said groove, a pair of contacts associated with said switch block, an operating member having a spring attached thereto, said operating member being adapted with said spring attached thereto to be so introduced into said groove that said spring is thereby projected through said spring receiving opening and a circuit closer adapted to be attached to the projecting end of said spring and assume an operating position upon said switch block.
13. In an electric switch mechanism, a casing, a switch unit adapted to be assembled exteriorly of and thereafter introduced as a unit into said casing, said unit comprising a switch block having a groove formed therein and a spring receiving opening communicating with said groove, a pair of contacts having interlocking engagement with said switch block whereby they are held against longitudinal movement with respect to each other, an operating member having a spring attached thereto, said operating member being adapted with said spring attached thereto to be so introduced into said groove that said spring is thereby projected through said spring receiving opening and a circuit closer adapted to be attached to the projecting end of said spring
- and assume an operating position upon said switch block.
14. In an electric switch mechanism, a casing, a switch unit adapted to be assembled exteriorly of and thereafter introduced as a unit into said casing, said unit comprising a switch block having a pair of contact receiving openings formed therein in an angular relation to each other and provided with a groove open at one side of said switch block and communicating with a spring receiving opening formed in said switch block, an operating member having a spring attached thereto, said operating member being adapted, with said spring attached thereto, to be so introduced into said groove from the open side thereof that said spring is thereby projected through said spring receiving opening and a circuit closer adapted to be attached to the projecting end of said spring and retained by said spring in operating position upon that face of said switch block which is opposite the side having the groove formed therein.
15. In an electric switch mechanism, a casing, a switch unit adapted to be assembled exteriorly of and thereafter introduced as a unit into said casing, said unit comprising a switch block having a spring receiving opening formed therein, a circuit closer arranged above said block, an operating member slidable across said block and a spring drawing upwardly on said operating member and holding said circuit closer down upon said block and adapted to be inserted from below through said spring receiving opening and thereafter engage said circuit closer.

In testimony whereof, I have affixed my signature to this specification.

WILLIAM C. MILES.
